[57] ABSTRACT

An apparatus for the removing of deposits of fibers and/or foreign bodies in spinning rotors is described, the apparatus being particularly useful in conjunction with spinning rotors on open end spinning frames. The frame has at least one spinning rotor, a pneumatic cleaning instrumentality being associated with each rotor. A thread monitor is provided which senses the presence or tension in the thread and initiates a reduction in the rpm of the spinning rotor in the case of thread breakage. A timing device, responsive to the output from the thread monitor indicative of thread breakage, controls the cleaning instrumentality to effect the start of cleaning after a predetermined lapse of time from the instant the monitor signals that the yarn has broken and to effect the end of the cleaning operation upon the lapse of an additional period of time.

APPARATUS FOR CLEANING SPINNING ROTORS

BACKGROUND OF THE INVENTION

This invention relates to an apparatus for removing 5 of deposits in spinning rotors. The invention relates, more particularly, to an apparatus for the removal of deposits in spinning rotors on open end spinning frames, wherein the open end spinning frame has at least one spinning rotor. A respective pneumatic cleaning instrumentality is operatively associated with each spinning rotor. The fibers and/or other foreign bodies not spun into the thread are freed from the rotor by the pneumatic cleaning instrumentality. A thread monitor is provided which initiates a continuous reduction of 15 the rpm of the spinning rotor in case of thread breakage.

When thread breakage occurs at a spinning location of an open end spinning frame, it is necessary to clean 20 the effected spinning rotor of deposits of fibers and/or foreign bodies prior to starting again the spinning, i.e. it is necessary to remove a deposited ring of delivered but unspun fibers which were not otherwise pulled out. The fibers lie in a fiber collection channel or groove. Foreign bodies which may collect in the groove also 25 need to be removed. Without such cleaning, the ring of fibers would either prevent the restarting of spinning altogether or the ring would create a defective bulge in the thread or yarn. Foreign bodies lying in the groove and which were very probably responsible for the thread breakage would lead to repeated thread breakage.

It is known to stop the spinning rotor for purposes of 30 cleaning and to clean out the fiber collection channel or groove, using a small brush. This technique requires a considerable expenditure of time. It is known from German Laid-Open Patent Application No. 1,560,301 to clean a spinning rotor by injecting pressurized air via a cleaning nozzle, terminating at the fiber collection channel or groove. For this purpose, the supply of fibers to be spun is stopped so that no further fibers are 35 delivered to the spinning rotor. Subsequently, all fibers still located in the fiber collection channel or groove of the spinning rotor are bound up, with the open end of a thread, and are pulled off of the spinning rotor using the thread. Finally, the spinning rotor is stopped and a suction airstream aspirates all still remaining fibers from the spinning rotor. In order to remove the foreign bodies, which are often firmly lodged in the fiber collection channel or groove and which are not removable by suction airstream, a pressurized airstream is applied to the fiber collection channel or groove, whose entire extent is led under this pressurized airstream by slow 40 rotation of the spinning rotor.

This known apparatus is expensive because it requires a special low speed drive for the spinning rotor and its operation technique is time-consuming.

Thus, it has been further proposed, as can be seen 55 from German Laid-Open Patent Application No. 1,685,904, to turn on the pressurized airstream simultaneously with switch-off of the drive means and with the beginning of braking of the spinning rotor. However, it has been found that, even when the rpm of the spinning rotor drops rapidly, the pressurized airstream is still unable to lift the fibers lying in the fiber collection channel or groove because of the centrifugal forces acting upon them. Consequently, the fibers in 60

the channel or groove are swirled together and compacted into a firm ring of fibers located in the fiber collection channel or groove. The thus compacted ring of fibers cannot, however, be blown out by the pressurized airstream either in its entirety or as separated fibers.

SUMMARY OF THE INVENTION

It is an object of the present invention to provide an 10 apparatus for removing deposits of fibers and foreign bodies in a spinning rotor, pneumatically using pressurized air, located in the fiber collection channel or groove, without the danger that a ring of fibers being undesirably compacted.

It is another object of the present invention to provide 15 an apparatus for removing deposits of fibers and foreign bodies in a spinning rotor, and without requiring a separate and special drive arrangement for driving the spinning rotor in slow drive.

The foregoing objects, as well as others which are to 20 become apparent from the text below, are achieved in accordance with the present invention by providing an apparatus for the removing of deposits in spinning rotors on open end spinning frames. At least one spinning rotor is provided. A respective pneumatic cleaning instrumentality is operatively associated with each spinning rotor. The fibers and/or other foreign bodies not 25 spun into thread are freed from the respective rotor by its associated cleaning instrumentality. A thread monitor is provided which initiates a continuous reduction of the rpm of the spinning rotor in the case of thread breakage. A timing device responsive to output from the thread monitor indicative of thread breakage, 30 controls the cleaning instrumentality to effect the start of cleaning after a predetermined lapse of time from the instant of thread breakage as signaled by the monitor. The timing device also effects the termination of the 35 cleaning operation upon the lapse of an additional period of time.

In case of thread breakage, according to the salient 40 novel aspects of this present invention, the thread monitor turns on the timing device which, after a first predetermined time period so chosen that the rpm of the spinning rotor has been reduced to an rpm permitting the effectiveness of the cleaning instrumentality, produces an enabling control signal which actuates the 45 cleaning instrumentality. After a second predetermined time interval, the timing device causes the cleaning instrumentality to become ineffective, a disabling control signal being produced for this purpose.

The suitable time periods of the first and second time 50 intervals can be simply determined by empirical experiment, and can remain valid for all spinning stations of the particular spinning machine. The second time interval is chosen so that during that time interval the cleaning apparatus fulfills its cleaning function under normal, expected circumstances.

BRIEF DESCRIPTION OF THE DRAWING

FIG. 1 is a partially schematic, partially sectional side view of an apparatus for removing deposits from spinning rotors on an open end spinning frame, drive and 55 cleaning members, as well as the associated control and switching elements being shown, according to an illustrative embodiment of the present invention.

FIG. 2 is a diagrammatic, detailed view of the rotor drive and braking arrangements of the apparatus of FIG. 1.

FIG. 3 is a graphic representation of the rpm versus time characteristic of an apparatus according to the present invention showing the cooperation of the rotor drive and the cleaning instrumentality, partly solid and partly broken lines showing the rpm of the spinning rotor as a function of the time.

DETAILED DESCRIPTION OF THE PREFERRED EMBODIMENTS

The spinning machine shown in FIGS. 1 and 2 includes a spinning rotor 1, carried in a bearing 2 and drivable by a tangential belt 4 which contacts a conventional whorl 3 of the spinning rotor 1. A cylindrical region of a stationary base plate 5 extends into the interior of spinning rotor 1. A substantially centrally located thread removal channel 6 is provided in the base plate 5. A closable pressurized air channel 7, which is connected to a pressurized air source 26 shown with dash-dotted lines, is connected via an air line also shown diagrammatically as a dash-dotted line for the sake of clarity.

By opening a valve 8, a pressurized airstream, developed by the pressurized air source 26, can pass through a blow nozzle 14 forming the outlet of the pressurized air channel 7 and can be delivered to a fiber collecting groove (channel) 25 of the spinning rotor 1 to effect the pneumatic cleaning thereof. A thread monitor 9', which includes a feeler 9, constantly senses or monitors whether a thread 15 pulled out through the thread channel 6 is still present or not, or is under proper tension or not. When the thread 15 is absent or when the thread tension relaxes, the thread monitor 9' delivers an electrical pulse to a control instrument 11 with which it is connected by a line 10. The control instrument 11 controls operating or setting members 12 and 13 which respectively open and close the air shut-off valve 8 associated with the pressurized air channel 7, the mechanical connections between each of the setting members 12, 13 and the valve 8 being shown diagrammatically as dashed lines. In addition, as illustrated, the control instrument 11 can control an operating member 16 which can move a pivotal lever 17 (FIG. 2) in a counter-clockwise direction and against the effect of a spring 19 tending to pull the pivotal lever 17 in clockwise direction up to a stop 18. The pivotal lever 17 is pivotally mounted at a locally fixed point 20 and is equipped with a roller 22 and a brake pad 24. As is usual, the spinning rotor 1 and the base plate 5 are located in a chamber (not shown).

In normal operation, the rotor 1 is driven by the tangential belt 4 at a high rpm n_1 (FIG. 3). In a manner not further shown, loose fibers are continuously collected in the fiber collection channel or groove 25 of the rotor 1 and are twisted into the open end of a forming thread, and the thread 15 is continuously pulled off to the outside through the channel 6.

When thread breakage occurs, or when the tension of a thread 15 is considerably reduced, this fact is sensed by the thread feeler 9 of the thread monitor 9'. The monitor 9' delivers a signal to the control instrument 11. The time of the occurrence of such a signal is indicated in the diagram of FIG. 3 by the symbol t_1 . Whenever such a signal arrives at the control instrument 11, the latter sends an electrical enabling signal

(actuating pulse) to the operational member 16, which consequently moves the pivotal lever 17 toward the whorl 3. As a result, the roller 22 lifts the tangential drive belt 4 from whorl 3 and the brake pad 24 is pressed against the whorl 3 so that, from the time t_2 on, the whorl 3 is braked. Thus, from time t_2 on, the rpm of the spinning rotor 1 continuously diminishes. Also at time t_1 , a timing device 27, contained within the control instrument 11 is turned on and after a time interval Δt_{13} , it delivers an enabling signal (electrical pulse) to the setting member 12. The time interval Δt_{13} is so chosen that at its end, the rpm of the spinning rotor 1 has been reduced to a value n_2 , which is such that the cleaning instrumentality constituted by the air source 26, the timer 27, and the blow nozzle 14 can effectively clean the rotor 1 by blowing, i.e. it can pneumatically clean its fiber collection channel or groove 25, because only this groove contains contaminations, foreign bodies, and fibers not spun into the thread 15, so that it is sufficient to clean the fiber collection channel or groove 25 pneumatically. The time interval Δt_{13} ends at a time t_3 . At this time t_3 , the control instrument 11 causes the generation of a control pulse which is fed to the setting member 12, which thereupon opens the valve 8, so that the cleaning instrumentality 26, 8, 7, 14 is effective to pass air, and pressurized air is blown out of the nozzle 14 into the fiber collection channel or groove 25 for cleaning the channel or groove 25. The valve 8 remains open until the control instrument 11 delivers another control pulse to the setting member 13 at the end of a predetermined, time interval Δt_{35} , i.e. at a point designated in the exemplary embodiment of FIG. 3 as t_5 , which causes the setting member 13 to close the valve 8 and to terminate the blowing of pressurized air out of the nozzle 14. The time interval Δt_{13} , at the termination of which the timing device 27 contained within the control instrument 11 delivers a control pulse to the setting member 12 for the purpose of opening the shut-off valve 8 is so chosen that at the time t_3 , the rpm of the spinning rotor 1 is already so diminished that the pneumatic cleaning can be fully effective. The length of this time interval depends on the operational rpm n_1 of the spinning rotor 1 and also on its inertial mass; further it depends on the force with which the brake pad 24 is pressed against the whorl 3 and it also depends on other factors and is suitably determined by experiments. The time interval Δt_{35} , during which the cleaning apparatus is effective because of the opened valve 8, is also suitably determined by experiments, so that the spinning rotor 1 will, under normal circumstances, be reliably cleaned of all deposits. Normally, it can be suitably provided that the control pulse for closing the shut-off valve 8 is delivered to the setting member 13 only when the spinning rotor 1 is already stationary or very nearly stationary.

Occasionally, it is not required to decelerate the spinning rotor 1 to a standstill. Thus, in many cases, it can be suitably provided that, after a predetermined time interval Δt_{14} , measured from time t_1 , the spinning rotor 1 is again connected with its drive belt 4 and accelerated thereby to its operational rpm n_1 , as is illustrated in FIG. 3 by the broken line. This time t_4 can be measured by the timing device 27 either starting from the time t_1 resulting in a time interval Δt_{14} or from time t_3 resulting in a time interval Δt_{34} . The control pulse triggered at time t_4 causes the control instrument 11 to deliver an operating pulse to the operating member 16,

the effect of which is that braking of the spinning rotor 1 is suspended and the spinning rotor 1 is reconnected with the tangential drive belt 4. In this case, too, it can be provided that the cleaning operation is terminated only at a time t_5 or at some other suitable time. Suitably, this time, at which the valve 8 is closed off again, is generally so chosen that the rpm of the spinning rotor 1 has not exceeded a value n_2 at this time, so that this time would lie within the time interval Δt_{35} .

It can be further suitable, according to the invention, to provide that, when a thread breakage occurs, the thread monitor 9' causes the release of the driving connection between the spinning rotor 1 and its tangential drive belt 4, so that, during each arrest of the machine, all spinning rotors are pneumatically cleaned.

It is to be appreciated that the foregoing detailed description and accompanying figures are set forth by way of illustration, not by way of limitation. Numerous other embodiments and variants are possible within the spirit and scope of the invention, the scope being defined by the appended claims.

What is claimed is:

1. In an apparatus for removing of deposits from at least one spinning rotor on an open end spinning frame, the apparatus including a respective pneumatic cleaning instrumentality operatively associated with each spinning rotor for freeing fibers and other foreign bodies, if any, not spun into thread from the respective rotor, and a thread monitor provided for initiating a continuous reduction of the rpm of the spinning rotor in

case of thread breakage, the improvement comprising a timing device responsive to output from said thread monitor indicative of thread breakage for controlling the cleaning instrumentality to effect the start of cleaning after a predetermined lapse of time from the instant of thread breakage as signaled by said monitor, said timing device also effecting the termination of the cleaning operation upon the lapse of an additional period of time.

5 10 2. An arrangement according to claim 1 including setting means and drive means, and wherein said timing device is operatively arranged to produce a control signal which is coupled to said setting means for reconnecting said spinning rotor with said drive means.

15 3. An arrangement according to claim 2, wherein said timing device also starts its working cycle whenever the entire apparatus is stopped, i.e. when all of the spinning rotors of said apparatus are stopped.

4. An arrangement according to claim 1 including drive means for said rotor, and wherein said thread monitor produces an output signal for effecting release of the driving connection between said spinning rotor and its said drive means upon the occurrence of a signal indicative of thread breakage.

20 25 5. An arrangement according to claim 1, wherein said timing device also starts its working cycle whenever the entire apparatus is stopped, i.e. when all of the spinning rotors of said apparatus are stopped.
